Halske Aktiengesellschaft, Wernerwerk, Sie-
mensstadt, near Berlin, Germany**

**Application January 25, 1937, Serial No. 122,154
In Germany January 27, 1936**

18 Claims. (Cl. 179—7.1)

The invention relates to telephone systems in which subscribers' meters arranged in the exchange are operated during a call and more especially to such systems in which the meters are influenced by a meter advancing device for example, an impulse sender at relatively short intervals of time which according to the traffic direction and thus according to the value of the call, can be of varying durations. If in such systems subscribers' stations are to be provided with fee indicators, difficulties are involved since it is not feasible to operate these fee indicators simultaneously with the meters, for the very frequent application of a potential operating the fee indicator at the subscriber's station while a call is in progress causes inconvenience to the calling subscriber.

The invention aims at enabling fee indicators to be operated efficiently at subscribers' stations while avoiding any inconvenience to the subscriber and achieves this in that switching means are provided, which when a call becomes chargeable, enable the fee indicator at the subscriber's station to be influenced at a different time and/or by impulses whose number is less than the number of impulses operating the subscriber's meter at the exchange.

According to the invention the fee indicator of a subscriber's station engaged in the call can be advanced at the end of the call by the same as or by a smaller number of impulses than the number of impulses operating the meter in the exchange during the call.

The operation by a smaller number of impulses enables a more rapid release of the connecting devices in the exchange which have to be maintained set while the metering impulses are passing. It can, however, only be applied in practice when strict correspondence between the value indicated at the fee indicator and the value indicated at the subscriber's meter does not matter because, since for each 10, 20, or more steps of the meter in the exchange the fee indicator is only advanced one step, the value indicated at the fee indicator is higher or lower than that indicated at the subscriber's meter according as to when the criterion for advancing the fee indicator is given, i. e., either on commencing or terminating a group of 10, 20 or more metering impulses.

If the advancing of the fee indicator is effected by a number of impulses less than the number of impulses influencing the meter in the exchange the fee indicator can also be advanced during the call. The transitory application of potential to

the speaking line can then be recognized by the calling subscriber and serves to indicate to the subscriber the advancing of the fee indicator and the amount of the fee to be paid.

According to the invention one and the same meter advancing device can operate both the subscriber's meter in the exchange and also the fee indicator. Alternatively, of course, two metering advancing devices can be provided, one for the subscriber's meter and the second for the fee indicator.

Embodiments of the invention are represented in the drawings, comprising Figs. 1 to 4, inclusive. Fig. 1 shows by way of example a subscribers' station and a line therefor extending to an exchange; a fee indicator is shown at the substation and a subscriber's meter at the exchange, together with controlling devices at the exchange for operating the fee indicator and the meter in accordance with the invention. 20 Figs. 2, 3 and 4 disclose modified controlling arrangements. All details which do not help to explain the invention have been omitted for the sake of clarity.

It is assumed that the call becomes chargeable from the moment at which the called party replies. Naturally the instant at which a call becomes chargeable can occur at other time, for example when the calling impulse becomes operative, on seizing a connecting device over the pre-selecting stage or stages, or when the calling subscriber transmits the first numerical impulse train.

In the case of the embodiment according to Fig. 1 when the preselector of the calling subscriber T_n has become set on a free connecting device the following circuit, which guards the connecting device chosen, is set up after the T-relay has energized; negative, off normal contact of the preselector, $2t$, winding II of relay T , 40 3, 4, relay C , $5k$ and positive. The speaking leads are switched through at contacts $6t$ and $7t$. At contact $8t$ the subscriber's meter GZ is connected to the special wiper 9 . Relays A and B are energized in the feeding circuit. The slow-to-release 45 relay VI is energised over $10a$ and this holds relay C over contact $11v1$ independently of contact $5k$ which opens on the first numerical impulse, at contacts $12v1$ and $13v1$ prepares for the impulse transmission to the meter advancing device Zf 50 and at contact $14v1$ prepares the circuit for the driving magnet Dzf of the meter advancing device. Contact $15v1$ is opened in the circuit of the release magnet Da of the meter advancing device. 55

The discriminator ML is set by the impulses transmitted by the calling subscriber which characterize the traffic direction and thereby the value of the call and this switch on its first 5 step closes contact 16km1 and opens contact 17km1. It will be assumed that the call is directed to the second fee zone and accordingly wipers 22 and 23 of the switch ML are set on contacts 24 and 25. When the called subscriber replies relay 10 Zr is energized in a manner which will not be described in detail by the application of negative battery to the lower speaking lead. Relay Zr closes contact 18zr, 19zr, and 20zr.

The meter advancing device Zf is assumed to 15 consist in the present embodiment of a rotary switch with a larger number of contacts. Two wipers zf1 and zf11 and zf2 and zf12, etc., are provided for each traffic direction and hence for every possible value which can be charged. The 20 subscriber's meter in the exchange is operated over the wipers zf1 and zf2 and the contact banks associated with them while zf11 and zf12, etc., are provided for controlling the fee indicators. It will further be assumed that for every 10 impulses 25 to be transmitted to the subscriber's meter one impulse is transmitted to the fee indicator so that on transmitting 1, 11, 21, etc., metering impulses one impulse is transmitted to and operates the fee indicator, and that moreover, the fee indicator 30 is influenced during the progress of a call.

As soon as the fee becomes chargeable, which is assumed to be when the called subscriber replies, the circuit for magnet Dzf is closed at contact 20zr; negative, 20zr, 14v1, 16km1, Dzf, interrupter 21 and positive. All the wipers of the meter advancing device (metering impulse sender) are stepped forward at intervals of time determined by the interrupter 21. When the wipers of the metering impulse sender pass on to 40 the first contact the subscriber's meter in the exchange and the fee indicator are operated simultaneously. The circuit for the subscriber's meter is as follows: positive, 26, zf2, 24, 22, 18zr, 12v1, 9, GZ, 8t, 1, and negative. For the purpose 45 of influencing the fee indicator GA relay Z is energized by connecting positive battery to the guarding and holding lead over a low resistance (VR): positive, contact 28vr, VR, 27, zf12, 25, 23, 19zr, 13v1, 4, 3, relay Z in parallel with winding 50 II of relay T, 2t, 1 and negative. Relay Z closes its contacts 29z, 30z, and 31z. Over contact 29z and 30z alternating current is simultaneously applied to both speaking leads and thereby the fee indicator GA at the subscriber's station is operated. A control meter KZ is energized over contact 55 31z.

Since the wiper zf12 remains on contact 27 until magnet Dzf is next energized by the interrupter 21 relay Z is prevented from energizing and 60 thereby breaking the speaking leads at contacts 32z and 33z for a prolonged period in that the slow-to-operate relay VR breaks the energizing circuit of relay Z at contact 28vr, and at contact 65 68vr connects up a resistance 69 tending to cause relay Z to release. Relay VR remains energized over 69.

Instead of disconnecting the speaking leads on the energizing of relay Z the arrangement can of course be adapted so that the alternating current 70 is merely applied simultaneously to the two speaking leads.

Through the application of alternating current to the speaking leads whether the speaking leads are broken or not the subscriber in conversation 75 is considerably inconvenienced. Since, however,

this only takes place at large intervals of time—according to the assumption only once for every 10 impulses transmitted to the subscriber's meter GZ—this inconvenience can be put up with especially since the subscriber provided with the fee indicator can deduce from this how often his fee indicator is operated. He is thus in a position to reduce the cost of the call by reducing the time taken.

Since the call is set up in the second fee zone 10 positive battery is connected to every second contact in the bank of the metering impulse sender traversed by wiper zf2 and to every twentieth contact in the contact bank of wiper zf12.

When the call is completed and the receiver is 15 replaced by subscriber Tn relays A and B release and disconnect relay VI. At contacts 12v1 and 13v1 the leads for transmitting the metering impulses are broken, and at contact 14v1 the driving magnet Dzf is disconnected. At contact 15v1 the 20 release magnet of the metering impulse sender is connected up: negative, 15v1, 17km1, Da, 34kzf, and positive. The metering impulse sender Zf is restored to normal.

The release of the discriminator ML and of the 25 preselector VW takes place in any known manner.

In the further embodiments (Figs. 2-4) the switching elements which correspond to those in Figure 1 have the same reference numbers as 30 they have in this figure.

In the case of the embodiment according to Fig. 2 the fee indicator is influenced at the end of the call. For this purpose the meter impulse sender is so constructed that it is stepped in one direction by a driving magnet Dzf1 and is restored in steps to the rest position by a second driving magnet Dzf2. A relay V2 is also provided which maintains the connecting path to the calling station so long as the meter advancing device 40 Zf is in the working position. Relay V2 is operated over a contact 34kzf which is closed on the first switching step of the meter impulse sender. It holds up relay C which controls the final disconnection of the connecting path and also the 45 cut-off relay T of the subscriber's line over contact 35v2 and in addition relay Zr independently of the succeeding connecting devices in a manner which will not be described in detail. Since during the advance of the meter impulse sender in 50 the course of a call, no impulses are to be transmitted to the fee indicator, the connection between the guarding and holding lead 4 and wiper 23 of the discriminator switch is broken at contact 36v1. At the end of the conversation and 55 after relays A, B and VI have released contacts 36v1 and 37v1 are closed. Over contact 37v1 the magnet Dzf2 which restores the impulse sender to the rest position is energized over: negative 20zr, 16km1, 37v1, Dzf2, interrupter 38, positive. 60 The interrupter 38 transmits impulses in more rapid succession than the interrupter 21 and these advance the metering impulse sender in time units corresponding to the tariff. The wipers of the metering impulse sender remain during the 65 restoring motion on a contact only so long as is necessary to ensure a satisfactory operation of the fee indicator by the relay applying the operating current.

Each time that the wiper connected by the discriminator ML and which serves to operate the fee indicator reaches an earthed contact positive battery is applied to lead 4 over contacts 23, 19zr and 36v1 and accordingly relay Z is energized in the subscriber's line and transmits the 75

metering impulses to the fee indicator in the manner described with reference to Fig. 1.

In the case of this embodiment the relay VR shown in Fig. 1 can be omitted. A low resistance 5 would then be connected up in its place.

If the fee indicator is to be operated by the same number of metering impulses as is the meter in the exchange the wiper $zf11$ and $zf12$ (Fig. 1) are not necessary. On the return motion of the 10 metering impulse sender relay Z is then energized over the contacts effecting the influencing of the subscriber's meter in the exchange during the forward motion, for example, the contacts passed over by wiper $zf2$. In arrangement of this 15 sort the wiper traversing this contact bank is connected over wiper 22 of the discriminator switch and contact 39v1 to lead 4 as shown in dotted lines in the figure by means of relay V1. The branch from 4 over contacts 26v1, 192r, etc., 20 may then also be omitted.

In the case of the arrangement according to Fig. 3 a special relay GAr which characterizes the connection of the subscriber's station to the fee indicator is provided. This is energized by 25 the closing of contact 40c. It closes its contacts 41gar, 42gar and 43gar. The provision of relay GAr enables both the maintenance of the connecting path to the calling subscriber by relay V2 and the switching through of the branch of lead 30 4 enabling the operation of relay Z at the subscriber's line to take place only if a subscriber having a fee indicator has been connected to the connecting device common to subscribers with and without fee indicators.

25 A relay GAr can also be provided in the embodiment according to Fig. 1. The switching through of the branch of lead 4 to wiper 23 of the discriminator switch would then be dependent upon its energizing at contact 44gar.

40 In the embodiment according to Fig. 4 two metering impulse senders ZfI , $ZfII$ are provided one for operating the subscriber's meter and the second for operating the fee indicator. The influencing of the subscriber's meter takes place in 45 the manner already described. On the first metering impulse the relay G corresponding to the traffic direction and thus to the value of the call, is energized in the metering circuit which passes over the wipers of the discriminator switch 50 and of the metering impulse sender. Since it may again be assumed that the call is set up in the second traffic direction and accordingly wiper 22 of the switch ML rests on contact 24, relay G2 is energized over its winding I on the 55 first metering impulse. It locks up over the off normal contact 50kzf1, its contact 51g2 and its winding II.

There are assumed to be five traffic zones present. For calls in the zone 1 a fee indicator is 60 operated by one impulse for each time unit and for calls in the second zone by two impulses etc. Accordingly the first, sixth, eleventh etc., contacts in the contact bank of wiper $zfII1$ of the metering impulse sender $ZfII$ is characterized by 65 relay G1 (first zone). The second, seventh, etc., contacts in the same contact bank are characterized by contacts of relay G2 etc. In order to ensure the transmission of two impulses for each unit of time in the case of calls in zone 2 relay G2 when it has been operated, over contact 52g2, also brings up relay G1, thus in the 70 case of calls in zone 2 contacts 53g2 and 54g1 are closed so that during the motion of the metering impulse sender $ZfII$ impulses are transmitted for energizing relay Z at the subscriber's station 75

when contacts 1, 2, 6, 7, 11, 12, etc., are passed over.

If a call is established to zone 3 then a relay G3 (not shown) characterizing this traffic direction energizes relay G2 over contact 55g3 and this 5 energizes relay G1 over contact 52g2. Contact 56g3 is then also closed and accordingly impulses are transmitted when the wiper $ZfIII$ passes over contacts 1, 2, 3, 6, 7, 8, etc., of the contact bank.

In the branch of lead 4 and in the circuit of relay V2 contacts 42gar and 41gar can be operated again or not. On the termination of a call in a system having a meter advancing device as in Fig. 4 the contacts 12v1 and 14v1 are opened by 10 the release of relay V1 and contacts 36v1 and 37v1 closed. The impulse sender $ZfII$ operates over: negative, 37v1, 202r, off-normal contact 57kzf1, $DzfII$, 59w, 38, positive. Each time the wiper $ZfIII$ passes on to a contact to which positive battery is applied by one of the contacts 20 54g1, 53g2, etc., relay Z is energized and transmits an impulse to the fee indicator. When the meter advancing device $ZfII$ reaches the same position as is occupied by the meter advancing 25 device ZfI relay W is energized over the special interconnected contact banks traversed by wipers $zfI3$ and $zfII2$. The circuit for this relay was prepared at off normal contact 59kzfII on the first step of the meter impulse sender $ZfII$. It 30 interrupts the further transmission of impulses to the relay Z by opening the circuit to the driving magnet $DzfII$ at contacts 59w and the branch from lead 4 at contact 60w. At contact 61w relay V2 is disconnected and releases and brings 35 about the release of the connecting path to the calling station. Over contact 62w the release magnet $Da1$ of the meter impulse sender ZfI is operated over off-normal contact 63kzf1 and the release of magnet $Da2$ of the metering impulse 40 sender $ZfII$ is operated over contact 64kzfII. Both meter advancing devices are restored to 45 normal. When they reach this position all the off normal contacts take up their rest position. The energized traffic direction-characterizing relays G1, G2, etc., have released as have also the releasing magnets.

If in the case of the embodiment according to Fig. 4 the relay GAr characterizing the connection of a subscriber having a fee indicator is provided 50 the connection of the driving magnet $DzfII$ can be dependent upon the energizing of this relay as is indicated in the drawings by dotted lines. The meter advancing device $ZfII$ would then not be set in motion when a subscriber not provided 55 with a fee indicator was connected up. The release of the only operated metering impulse sender ZfI in the case of such calls would then take place immediately on the release of relay V1 60 independently of relay W.

The metering impulse sender $ZfII$ can transmit either the same or a smaller number of impulses than the metering impulse sender ZfI for each call. In the latter case naturally a switch having a smaller number of switching positions can be 65 used for the metering impulse sender $ZfII$ than for the metering impulse sender ZfI .

By suitably wiring the two contact banks traversed by the wiper $ZfI3$ and $zfII2$ and by corresponding connecting potential to the contact 70 bank traversed by wiper $zfII1$ the stepping of the fee indicator can be adjusted to the particular tariff obtaining. Also in the case of the embodiment according to Fig. 1 by varying the connection of potential to the contact banks traversed 75

by the wipers of the metering impulse sender Z_f the latter can be adjusted to any tariff desired. Instead of sending a metering impulse to the subscriber's meter GZ at shorter or longer intervals of time as is shown in Fig. 1 in which, in the case of connections in the zone 1, an impulse is transmitted after each third step of the impulse sender which is advanced at definite intervals of time, and in the case of calls in the traffic zone 2 after every second switching step of the impulse sender, the system can be arranged so that on the commencement of each time interval, which has the same length in the case of all calls independent of the traffic zone with which the call is concerned, a varying number of impulses can be transmitted in succession corresponding to the traffic zone in question.

What is claimed is:

1. In a telephone system, subscribers' lines, an exchange in which said lines terminate, means in the exchange for extending a connection from a calling one of said lines to another line, a fee indicator on each line responsive to metering impulses transmitted thereover both during and after a call, a meter for each line, means in the exchange for transmitting impulses to operate the meter of a calling line during a connection, and other means controlled thereby independently of the operation of said meter for transmitting metering impulses over the line to the fee indicator.

2. In a telephone system, subscribers' lines, an exchange in which said lines terminate, means in the exchange for extending a connection from a calling one of said lines to another line, a fee indicator on each line, a meter for each line, a controlling device, means for operating said device for transmitting a series of impulses to operate the meter of the calling line during a connection and for transmitting another series of impulses to the fee indicator of the calling line independently of the operation of said meter.

3. A system as described in claim 2, in which the controlling device transmits a series of impulses to the meter during the connection and another series of impulses to the fee indicator on termination of the connection.

4. A system as described in claim 2, in which for the same connection, the number of impulses in the series transmitted to the fee indicator is less than the number in the series transmitted to the meter.

5. A system as described in claim 2, in which the controlling device steps in one direction for transmitting the series of impulses to the meter and restores to normal to transmit the series of impulses to the fee indicator during such restoration.

6. In a telephone system, subscribers' lines, an exchange in which said lines terminate, means in the exchange for extending a connection from a calling one of said lines to another line, a fee indicator on each line responsive to metering impulses transmitted thereover both during and after a call, a meter for each line, a first controlling device, a second controlling device, means in the exchange for causing said first controlling device to transmit a series of impulses to the meter of the calling line during a connection and for causing said second controlling device to

transmit metering impulses to the fee indicator of the calling line.

7. A system as described in claim 6, in which the metering impulses transmitted from the second controlling device are controlled by the first controlling device.

8. In a system as described in claim 2, in which the fee indicator receives impulses on termination of the connection, and means controlled by the controlling device for maintaining a connecting circuit between said device and the calling line.

9. A system as described in claim 6, in which for the same connection the number of metering impulses transmitted to the fee indicator by the second controlling device is less than the number of impulses in the series transmitted to the meter by the first controlling device.

10. A system as described in claim 6, in which the second controlling device transmits the metering impulses to the fee indicator on termination of the connection.

11. In a system as described in claim 6, in which the fee indicator receives impulses on termination of a connection, and means controlled by one of the controlling devices for maintaining a connecting circuit between said device and the calling line.

12. In a system as described in claim 6, a zoning device and means for operating said device to control the number of metering impulses transmitted by the second controlling device.

13. In a system as described in claim 6, a zoning device and means for operating said zoning device when the first controlling device is operated, to control the number of impulses transmitted.

14. In a system as described in claim 6, a plurality of zones, a relay for each of the zones for controlling the number of impulses transmitted by said devices, one of the relays operated responsive to a connection between two lines, and means effective on operation of any one of the relays to operate the relay of the next less remote zone.

15. In a system as described in claim 6, in which one series of impulses are transmitted over one lead to the meter of the calling line and the other series of impulses are transmitted over another lead to control the fee indicator of the calling line.

16. In a telephone system as claimed in claim 6, in which only certain of the subscribers' lines are provided with fee indicators, the provision of means associated with each line having a fee indicator for rendering said second controlling device operative.

17. In a telephone system as claimed in claim 1, in which only certain of the subscribers' lines are provided with fee indicators, the provision of means associated with each line having a fee indicator for rendering said transmitting means operative.

18. In a telephone system as claimed in claim 2, in which the series of impulses to the meter of the calling line are transmitted over one lead and the series of impulses controlling the fee indication of the calling line are transmitted over another lead.
